US0D1047951S

(12) **United States Design Patent** (10) Patent No.: **US D1,047,951 S**
(45) Date of Patent: ** Oct. 22, 2024

(54) **HANDHELD TRANSLATOR**

(71) Applicant: **SHENZHEN TIMEKETTLE TECHNOLOGIES CO., LTD.**, Shenzhen (CN)

(72) Inventor: **Wei Liu**, Honghu (CN)

(73) Assignee: **SHENZHEN TIMEKETTLE TECHNOLOGIES CO., LTD.**, Shenzhen (CN)

(**) Term: **15 Years**

(21) Appl. No.: **29/854,060**

(22) Filed: **Sep. 21, 2022**

(51) LOC (14) Cl. **14-02**

(52) U.S. Cl.

USPC **D14/158**

(57) **CLAIM**

The ornamental design for a handheld translator, as shown and described.

DESCRIPTION

FIG. 1 is a front, bottom and right side perspective view of a handheld translator, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the handheld translator, which form no part of the claimed design.

1 Claim, 8 Drawing Sheets
